UNITED STATES PATENT OFFICE.

WILLIAM GUSTAVUS DEMAREST, OF METUCHEN, NEW JERSEY.

WALL CONSTRUCTION.

1,426,048.

Specification of Letters Patent. Patented Aug. 15, 1922.

Application filed September 2, 1920. Serial No. 407,642.

To all whom it may concern:

Be it known that I, WILLIAM GUSTAVUS DEMAREST, a citizen of the United States, and a resident of Metuchen, in the county of 5 Middlesex and State of New Jersey, have invented certain new and useful Improvements in Wall Constructions, of which the following is a specification.

The present invention relates in general 10 to wall constructions, and more particularly to a composite brick and tile wall construction.

In the composite wall construction of this 15 general character widely used, the tile and brick facing which comprise the wall are practically always burned to vitrification so that the mortar does not enter into a close bond with the tile or brick. Again, as it is essential to strength, the brick facing embodies at regular intervals header courses. 20 In order to properly organize the tile with the ordinary courses and with the header courses of the brick facing a peculiar construction and arrangement of the tile is necessary. 25 This construction and arrangement as heretofore proposed has been such as to prevent the air passages through the tile from being continuous and also to preclude the use of the full load bearing strength of 30 the burned clay comprising the tile, so that the tile constitutes a dead load or weight. As a consequence of these features serious 35 objections and disadvantages are met with for in the first instance the rain and other moisture which penetrates the wall due to the low character of the bond between the mortar and the elements of the wall find its way into the interior of the building and works serious damage and finally the dead 40 weight or load of the tile necessitates additional steel framework to support the same.

One of the principal objects of the present invention is to overcome these disadvantages and objectionable features by providing a composite wall construction in 45 which the tile and brick facing are properly organized to obtain a high degree of strength and in such manner as to provide continuous air passes through the tile so as 50 to arrest and dissipate the moisture finding its way into the wall and prevent the moisture from penetrating through the wall into the interior of the building; in which the full load bearing strength of the burned clay 55 comprising the tile is taken advantage of and utilized to sustain the building con-

struction to thereby reduce the amount of steel framework necessary and in which the tile of the wall is of simple and durable construction, easy and inexpensive to manufacture and susceptible of being assembled into the wall construction with a minimum handling and a minimum expenditure of labor.

Other objects and advantages of the invention reside in certain novel features of 60 construction, combination and arrangement of parts as will be hereinafter more fully described and particularly pointed out in the appended claim, reference being had to the accompanying drawings forming part 65 of this specification, and in which:

Figure 1 is a perspective view of a portion of a wall embodying the invention;

Figure 2 is a side elevational view of the tile embodied in the wall construction shown 75 in Figure 1;

Figure 3 is a plan view thereof.

Referring to the drawings it will be seen the invention contemplates a composite wall construction which includes in all of its 80 embodiments, a brick facing designated generally at F and preferably comprising ordinary courses 5 of facing brick having at regular intervals, preferably at every sixth course, header bricks 6. Tile, designated 85 generally at 7, is associated with the brick facing and in all forms of the invention is so constructed and arranged as to form with the brick facing an organized wall construction. The facing brick, the tile, 90 and the tile and the facing brick are bound together in the usual manner by mortar or the like M.

Referring especially to Figures 1, 2, and 95 3, the tile T which enters into the wall construction in this embodiment of the invention consists of relatively large rectangular blocks 7 of cellular construction and embodying vertical webs defining an inner series of vertical openings and an outer 100 series of vertical openings, designated at 8 and 9, respectively. The blocks 7 are preferably of a height equal to the height of the five ordinary courses 5 of the brick facing and these blocks are arranged in a course 105 adjacent and immediately to the rear of the ordinary courses 5, as shown in Figure 1. The header courses of the facing extend over the ends of the blocks 7 and overlap the outer vertical openings 9 but they terminate 110 short of the inner vertical openings 8, as clearly shown in Figure 1.

The tile T includes shoulders or relatively small block portions 10 arranged adjacent and immediately to the rear of the header courses 6 of the facing brick. The 5 relatively small block portions 10 in this embodiment of the invention are preferably formed by extending the webs of the rectangular block 7 at the rear of the block. The extended webs which constitute the 10 block 10 define vertical openings 8^a which are continuations of the openings 8 of the blocks 7. The openings 8^a of the blocks 10 of one course of the tile are alined with the openings 8 and 8^a of the adjacent courses 15 so as to provide continuous air passages through the wall. Moreover the vertical webs of which the blocks of the courses are constituted are also alined so that the webs of the blocks of one course are superposed 20 on the webs of the blocks of the lower course and in this manner the full load bearing strength of the burned clay comprising the tile is utilized. The header bricks 6 extend in between the ends of the blocks 7 and have 25 their inner ends spaced from the relatively small block portions 10 to provide a gap A and to complete the organization of the wall construction.

It is thus seen that the construction and 30 arrangement of the tile and of the brick facing is such that the tile and the brick facing are highly organized and bonded to constitute a strong and durable wall construction. The organization is such that 35 continuous air passages are provided which serve to arrest the progress of any moisture which finds its way into the wall and precludes the moisture from penetrating the wall into the interior. The moisture is taken 40 up by the air in the openings and dissipated in this manner. And again in all of the

embodiments of the invention the webs which constitute the tile construction are alined and superposed so that the positive and continuous structure of the tile is 45 brought into action and functions to sustain the construction. In this manner the full or maximum load bearing strain of the burned clay constituting the tile is taken advantage of and no portion of the tiling 50 constitutes a dead load or weight which must be supported by the steel framework.

I claim:

A composite brick and tile wall construction comprising in combination with a brick 55 facing having ordinary courses and header courses, courses of tile including relatively large blocks arranged adjacent the ordinary courses and constructed of vertical webs defining inner and outer vertical openings, said 60 header courses of the facing extending over the ends of said relatively large blocks and overlapping the outer vertical openings thereof and terminating short of the inner vertical openings, said large blocks having 65 relatively small block portions at one end disposed behind the header courses and spaced therefrom and comprising integral extensions of vertical webs of said large blocks, said web extensions defining vertical 70 openings, the vertical openings of the relatively small block portions being alined with the inner vertical openings of the relatively large blocks, and the inner vertical openings of the large blocks and the vertical openings 75 of the small block portions being in open and direct communication to define continuous air passages through said walls whereby passage of moisture entirely through the wall is prevented and the moisture is dissipated.

WILLIAM GUSTAVUS DELAREST.
